(57) **CLAIM**

The ornamental design for a dogleg modular bagging area extension device, as shown and described.

DESCRIPTION

FIG. 1 is a perspective view of a dogleg modular bagging area extension device.

FIG. 2 is a front view thereof;

FIG. 3 is a back view thereof, with the unclaimed environmental structure removed for clarity of the illustration;

FIG. 4 is a left side view thereof;

FIG. 5 is a right view thereof;

FIG. 6 is a first top view thereof; and,

FIG. 7 is a bottom view thereof.

The broken lines depict environmental structure and form no part of the claimed design.

1 Claim, 7 Drawing Sheets
